VENTILATING DEVICE

Glenn O. Smith, Moline, and Dallas G. Reddick, East Moline, Ill., assignors to Smith Filter Corporation, Moline, Ill., a corporation of Illinois

Application September 24, 1956, Serial No. 611,479

5 Claims. (Cl. 98—115)

The present invention relates generally to ventilating systems and more particularly to filter cabinets having automatic fire dampers, grease traps, and other associated means, whereby sanitary, odorless and fire-safe conditions are easily maintained over cooking ranges, in kitchens, and the like.

The object and general nature of the present invention is the provision of a filter cabinet having a new and improved filter mounting, a new and improved fire safety damper that shuts off air flow through the unit in the event of a flash fire that may occur or be transmitted back of the filters, and new and improved grease and condensate trapping means, all neatly and conveniently arranged in a relatively inexpensive unit.

These and other objects and advantages of the present invention will be apparent to those skilled in the art, after a consideration of the preferred structure in which the principles of the present invention have incorporated and which have been illustrated in the accompanying drawings.

In the drawings:

Figure 1 is a perspective view, with certain parts in section, of a filter cabinet embodying the principles of the present invention.

Figure 2 is a sectional view taken along the line 2—2 of Figure 1.

Figure 3 is an enlarged sectional view, fragmentary in nature, taken along the line 3—3 of Figure 1.

Figure 4 is a horizontal sectional view, taken along the line 4—4 of Figure 1.

Figure 5 is an enlarged fragmentary view taken along the line 5—5 of Figure 2 showing the fire damper and automatic shut off switch actuated thereby.

Referring first to Figure 1, the reference numeral 10 indicates the filter cabinet in its entirety, the cabinet 10 having a top wall 11, which may serve as a warming shelf, end walls 12 and 13, which are generally triangular and flat, a back wall 14, a relatively narrow bottom wall 15, and front wall means 16 that is made up of an upper section 17 and a lower section 18, both lying in a common plane that extends generally upwardly and forwardly, as best shown in Figures 1 and 2. The front wall sections 17 and 18 are connected centrally by a specially formed channel member 19 having a relatively narrow web section 21, side flanges 22 and 23 and inwardly disposed laterally extending shouldered or abutment portions 25 and 26, the edges of which are folded back or beaded, as can best be seen in Figure 4. The ends of the channel member 19 are fixed, as by screws 27, to the upper and lower front wall sections 17 and 18, as shown in Figure 1.

The forward edges of the end walls 12 and 13 are formed by turning the stock back upon itself, as shown at 12a and 13a, Figure 4, and then, laterally inwardly of the plane of the front wall means 16, turning the edges inwardly to form filter-receiving shoulders or abutments 31 and 32, which lie in a plane that also passes through the abutment portions 25 and 26. Filters F¹ and F²

2

are normally disposed against the abutment portions 25, 26, 31, and 32, as can be seen in Figures 1 and 4. These filters may be of any suitable construction but preferably are made of several layers of aluminum mesh of various densities encased in a channel-like aluminum frame, substantially like the filter shown in U. S. Patent 2,602,521, issued July 8, 1952, to Glenn O. Smith, to which reference may be made if desired. The filters as employed in the present invention have frames 35 that are provided with holes 36 drilled or punched therein to facilitate drainage of grease and other condensate from the filters, as shown in Figure 3.

The filters F¹ and F² are supported in a particular way in the cabinet 10 to facilitate the rapid and convenient insertion and removal of the filters. As best shown in Figures 2 and 3, the upper edge of the lower front wall section 18 has a first part 18a that is folded back upon itself, and a second part 18b that is bent upwardly and inwardly, forming a right angle, and is beaded, thereby forming a shoulder or shelf to receive the lower edge of the filter so as to support the latter. At one or more points, openings 38 (Fig. 3) are punched or drilled in the lowermost corner of the filter support so that any grease or other condensate from the filter drips downwardly into the trough 40 that is formed by the bottom wall 15, the lower front wall portion 18 and an associated upwardly angled wall section 41 that lies between the wall portions 14 and 15. The upward divergence of the wall portions 18 and 41 thus provides a grease trough that is readily accessible for swabbing out with a damp cloth, or for cleaning in any other suitable way, and at one end of the trough 40 there is a drain 43 controlled by a valve 44 that provides for drainage after cleaning. When the filters are in place with their lower edges down against the lower parts 18a, described above, their upper edges rest against the associated upper sections 17. As illustrated in Fig. 4, when the filters are thus supported at their upper and lower edges, the sides are held in more or less close contact with the front faces of the abutment flanges 25, 26, 31, and 32.

It will be noted from Figure 2 that there is a space S in the cabinet 10 between the top wall 11 and the upper front wall section 17, and above the associated filter, and as shown in dotted lines in Figure 2, this space permits the filter to be raised until the lower edge of the filter clears the upper edge of the lower front wall section 18 after which the lower portion of each filter can be swung outwardly and downwardly and then lowered to entirely disconnect the filter from the cabinet. Thus, according to the present invention, the filters may easily and quickly be removed by simply lifting them up and out of the cabinet, with no latches, clamps or the like required. As will be seen from Figures 1 and 2, the filters extend upwardly and forwardly, away from the back wall, at about 45°. Handles 46 are provided at each side of each filter. When the filters are to be placed in position in the cabinet, all that it is necessary to do is to place the upper edge of the filter against the associated flanges 25, 31 or 26, 32, then raise the filter until the upper edge comes up against the top wall, as shown in dotted lines in Fig. 2, and then the lower edge of the filter can be swung in over the upper edge of the front lower wall portion 18a and then dropped down against the associated lower flange of part 18b, the upper part of the filter being supported by the front upper wall portion 17.

The top wall 11 is provided with an outlet in the form of an elongated opening 48, and communicating with the outlet 48 is a sweep type exhaust head 49 having a narrowed entrance section 51 converging upwardly to form a round opening 52 for simple and convenient coupling to a duct or the like that leads to the associated

exhaust fan (not shown) which may be of any suitable construction.

An automatic fire safety damper 56 is swingably connected to the cabinet 10 adjacent the juncture of the back and top walls 14 and 11, as by hinge means 57, and is biased for movement toward outlet closing position, over the opening 48, by suitable torsion spring means 58, Figure 5, the upper or back edge of the damper 56 being rolled to receive the hinge 57, as indicated at 59, the hinge 57 being a pin or the like, carried in brackets 61 fixed to the upper portion of the back wall 14. The fire damper 56 is releasably held in open position, lying snugly against the back wall 14, as shown in Figure 2, by a fusible link 63, the latter being made up of two parts connected together by material that fuses at about 270° F. The link 63 is connected at one end to the back wall 14 by a connector 64 and at the other end to the fire damper 56 by a similar connector 65. It will be noted that the fusible link 63 is located directly in back of the filters, and at any time that the temperature of the air passing through the filters exceeds 270° the parts of the link 63 separate, and immediately the fire damper closes by the rapid action of the springs 58. This prevents any passage of flames into the exhaust duct 49.

As will be seen from Figures 1 and 5, a switch unit 70 is mounted on the upper side of the top wall 11 and includes an operating lever 71. The unit 70 is of conventional construction, so far as the present invention is concerned, and is of the type that is normally closed, electrically interconnecting two leads 73 and 74 that extend to and control the fan motor. When there is, for example, a flash fire in the cabinet, and the link 63 releases the fire damper, the closing of the latter brings the damper into engagement with the switch lever 71 and the closing of the damper moves the lever 71 to a position interrupting the circuit to the exhaust fan. A suitable opening in the top wall 11 accommodates the lever 71.

While we have shown and described above the preferred structure in which the principles of this invention have been incorporated, it is to be understood that our invention is not to be limited to the particular details shown and described above, but that, in fact, widely different means may be utilized in the practice of the broader aspects of our invention.

What we claim, therefore, and desire to secure by Letters Patent is:

1. In a ventilating system, a cabinet having a back wall, a lower wall, a top wall, and means forming a downwardly and backwardly angled front wall having a filter-receiving opening, filter means carried in said opening, said front wall having a shoulder spaced below the lower edge of said filter-receiving opening but lying above said lower wall, said shoulder extending inwardly of the cabinet to provide a shelf below the lower edge of said opening and extending inwardly of the cabinet to receive said filter means with the lower edge of the latter above the lower wall of the cabinet and inwardly of the lower portion of said front wall, said shoulder having opening means in the lower portion lying inwardly of the inner face of the lower portion of the front wall means, whereby grease and other material may drain through said opening means but remain within the cabinet and inwardly of the filter means, so that the lower portion of the interior of the cabinet serves as a trap for grease, moisture and the like collected by the filter.

2. In a ventilating system, a cabinet having a back wall, a top wall, a bottom wall, the latter extending outwardly of the back wall a distance appreciably less than the top wall, and front wall means including a lower portion having an upper edge below which is disposed an inwardly directed filter receiving shoulder, filter means carried by said shoulder and having upper and lower marginal portions, said front wall means also including an upper portion substantially in the plane of the lower portion, said cabinet also including end walls fixed to the

ends of said back, top and bottom walls and said front wall means, each of said end walls having forward edge portions formed with laterally inwardly extending edge portions spaced inwardly from the plane of said upper and lower front wall portions a distance substantially equal to the thickness of said filter means, the upper ends of said laterally inwardly extending edge portions terminating at points below said upper wall and adjacent the lower edge of said upper front wall portion, whereby said laterally inwardly extending edge portions form filter-receiving shoulders adapted to engage the inner faces of the edge portions of said filter means, when the latter is in place, said upper front wall portion extending downwardly from the top wall a distance sufficient to support the upper marginal portion of the filter means when the lower marginal portion of the latter is carried by said first mentioned filter receiving shoulder, the distance between the upper edge of said lower front wall portion and the top wall adjacent said upper front wall portion being greater than the corresponding dimension of said filter means, whereby the latter may be inserted through the space between said upper and lower front wall portions and the upper marginal portion of the filter means at the inside thereof brought guidingly against said laterally inwardly extending edge portions, after which, guided by said edge portions, the upper end of the filter means may be inserted into the upper part of the cabinet behind said upper front wall portion, and the lower end of the filter means passed over the upper edge of the lower front wall portion and then brought up against said laterally inwardly extending edge portions and dropped down behind the upper edge of said lower front wall portion and against said first mentioned shoulder.

3. In a ventilating system, a cabinet having a back wall, a top wall, vertically-spaced apart upper and lower front wall sections forming therebetween a filter-receiving opening, filters disposed in said openings, end walls connected with the ends of said top and back walls and to the ends of said upper and lower front wall sections, the forward edge of each of said end walls being folded back upon itself and having a laterally inwardly extending part forming a filter-receiving part or abutment disposed inwardly of the plane of the front wall sections a distance corresponding generally to the thickness of the associated filter, a center member fixed at its upper and lower ends to the upper and lower front wall sections and including laterally outwardly filter-receiving flanges disposed back of the plane of said front wall sections a distance equal to the above mentioned distance, said center abutments thereby lying in the plane of said laterally inwardly extending filter-receiving parts, the lateral distance between each of said folded back end wall edges and the adjacent edge of the center member corresponding to the width of the associated filters, the distance between the upper and lower edges of the lower and upper front wall sections being less than the height of the associated filter and the distance between the upper edge of the lower front wall section and the top wall being appreciably in excess of the height of the filter, whereby each filter may be inserted from the front of the cabinet by first laying the upper edge of the filter against said abutments, then raising the filter until the lower edge can be passed over the upper edge of the lower front wall section and the filter brought into complete contact with both upper and lower portions of said abutments, and a filter-supporting shoulder on the inner face of said lower front wall section and disposed a distance below said latter upper edge such that when a filter is supported thereon the upper edge of the filter bears outwardly against the inner face of the upper front wall section.

4. In a ventilating system, a cabinet having a back wall, a top wall, and means forming a front wall having an opening in which filter means is disposed, there being a second opening in one of said top and back walls ad-

jacent the juncture of said top and back walls to provide for passage of air from the inside of the cabinet out through said second opening to a fan or blower unit, a fire damper hinged to one of said top and back walls adjacent said second opening and swingable, in the direction of air flow out through said second opening, from a position substantially flat against one of said top and back walls over into a position closing said second opening, suction from said fan or blower unit tending when operating to hold said damper closed tightly over said second opening, spring means acting against said damper to bias the same for movement in the direction of said air flow to a position closing said second opening, and a temperature-fusible link connected to the damper and one of said top and back walls for releasably holding said damper in position substantially flat against the associated wall so as not to obstruct normal air flow through said cabinet and out said second opening.

5. In a ventilating system, a cabinet having a back wall, a top wall, vertically spaced apart upper and lower front wall sections forming therebetween a filter-receiving opening, the forward edge of each of said end walls being folded back upon itself and having a laterally inwardly extending part forming a filter receiving abutment disposed inwardly of the plane of the front wall sections a distance corresponding generally to the thickness of the associated filter, the distance between the upper and lower edges of the lower and upper front wall sections

being less than the height of the associated filter and the distance between the upper edge of the lower front wall section and the top wall being appreciably in excess of the height of the filter, whereby the filter may be inserted from the front of the cabinet by first laying the upper edge of the filter against said abutments, then raising the filter until the lower edge can be passed over the upper edge of the lower front wall section and the filter brought into complete contact with both upper and lower portions of said abutments, and a filter-supporting shoulder on the inner face of said lower front wall section and disposed a distance below said latter upper edge such that when a filter is supported thereon the upper edge of the filter bears outwardly against the inner face of the upper front wall section.
